H. DUFFORD

RAIL ANCHOR

Filed Feb. 4, 1927

FIG. 1.

Inventor

H. Dufford

By *John Murphy Jr.*
Attorney

UNITED STATES PATENT OFFICE.

HERBERT DUFFORD, OF BUTLER, PENNSYLVANIA.

RAIL ANCHOR.

Application filed February 4, 1927. Serial No. 165,895.

This invention relates to and has for one of its objects to provide a novel, simple and inexpensive device for holding railway tracks to the required gage by preventing 5 any lateral movement of the rails in an outward direction with respect to each other, the device or rail anchor being adapted to be firmly secured to a cross tie and adapted to engage the outer base flange of a rail at 10 points spaced from the opposite sides of the tie.

With the foregoing and other objects in view, the nature of which will become apparent as the description proceeds, the invention 15 consists of the construction, combination and arrangement of parts hereinafter fully described and claimed, and illustrated in the accompanying drawing, wherein:

Figure 1 is a top plan view illustrating the 20 application of the rail anchor, and

Figure 2 is a view in side elevation of the parts shown in Figure 1.

Referring to the drawing by reference characters, 1 designates a rail and 2 a cross tie of a railway track. The rail anchor is 25 designated 3 and comprises a bar 4 which is secured upon the tie 2 inwardly of the rail 1 and diverging arms 5 which extend from an end of the bar to points beyond opposite 30 sides of the tie and engage the outer base flange 1^a of the rail. The bar 4 has its other end turned down to provide a retaining element 6 which is embedded in the tie 2 and which together with spikes 7 serve to firmly 35 secure the rail anchor in place. The free end portions of the arms 5 are offset downwardly as shown at 8, and said portions are positioned beneath the rail 1 and in contact with the under side thereof. The free ends of the 40 arms 5 are upturned to provide hooks 9 which engage the outer base flange 1^a of the rail 1.

In view of the manner in which the rail anchor is secured to the tie 2, and in view of the manner in which the rail anchor engages the rail 1, the rail is positively held 45 against outward displacement. The rail anchor 3 is especially adapted for use in connection with railway tracks of which the rails are insulated from each other for electrical purposes, inasmuch as it is not connected to opposite rails and will not therefore establish an electrical connection between the rails.

It should be understood that the drawing 55 is merely illustrative and does not pretend to give exact proportions. Furthermore, the said drawing is illustrative of a preferred construction, it being my expectation that various changes and modifications may be 60 made without departing from the spirit and scope of my invention.

What is claimed is:—

1. A rail anchor comprising a bar adapted 65 to be secured to a cross tie and having an end thereof turned down to provide a retaining element, and arms extending in divergent relation from the other end of the bar and provided at their free ends with rail 70 engaging hooks.

2. A rail anchor comprising a bar adapted 75 to be secured to a cross tie and having an end thereof turned down to provide a retaining element, and arms extending in divergent relation from the other end of the bar and having their free end portions offset downwardly and provided with rail engaging hooks.

In testimony whereof I affix my signature.

HERBERT DUFFORD.
